(No Model.)

I. CRUZAN.

SPRING BED BOTTOM.

No. 269,641.

Patented Dec. 26, 1882.

UNITED STATES PATENT OFFICE.

ISAAC CRUZAN, OF WAGONER'S STATION, INDIANA.

SPRING BED-BOTTOM.

SPECIFICATION forming part of Letters Patent No. 269,641, dated December 26, 1882.

Application filed October 20, 1882. (No model.)

To all whom it may concern:

Be it known that I, ISAAC CRUZAN, a citizen of the United States, residing at Wagoner's Station, in the county of Miami and State 5 of Indiana, have invented a new and useful Spring Bed-Bottom, of which the following is a specification, reference being had to the accompanying drawings.

Figure 1 is a top view of my improved spring bed-bottom. Fig. 2 is a side view. Figs. 3 and 10 4 are detail views of the edge and corner springs, and Fig. 5 is a perspective detail view of the adjustable head-rest.

Corresponding parts in the several figures 15 are denoted by like letters of reference.

This invention relates to spring bed-bottoms; and it consists in certain improvements in the construction of the same, which will be hereinafter fully described, and particularly point- 20 ed out in the claims.

In the drawings hereto annexed, A A represent the longitudinal and B B the transverse slats, constituting the main frame of my improved bed-bottom.

C is an adjustable head-rest, consisting of 25 longitudinal slats D and transverse slats E. The inner ends of the slats D are fitted between and adjoining the slats A of the main frame, to which they are hinged by a wire or rod, F, 30 passing through transverse perforations G in said slats A and D, thus making a very simple and durable hinge, which does not weaken the slats. The head-rest C has two supports, formed of wire bent so as to form T-shaped 35 loops H, the ends of which have eyes I, hinged upon a transverse wire, J, in the head-rest. The heads K of the supporting-loops H engage racks or ratchets L, formed of crimped wires, suitably attached to the longitudinal 40 slats A of the main frame. The loops H are connected by a cord, M, passing through perforations N in the rear ends of the slats D. By means of this cord the said loops or supports may conveniently be simultaneously op- 45 erated or released from the ratchets L when it shall be desired to lower the head-rest.

The springs of my improved bed-bottom may be secured in any suitable manner upon the slats B and E of the main frame and head- 50 rest. Of said springs the inner ones, O, may be of any suitable well-known construction. Those at the ends and edges, which are denoted by letter P, have their upper coils formed at their outer edges with straight ob-

long loops Q, and the corner-springs R have 55 their upper coils formed with angular loops S. The loops Q and S of adjoining springs are connected by links T, thus forming continuous straight edges to the bed-bottom, which prevent the edges of the mattress from 60 sagging. The angular loops S are connected with the corners of the frames by coiled springs U, which support said angular loops and the corners of the mattress.

The several springs constituting the bed- 65 bottom are connected by circular rings V, one of which is placed between each section of four springs, and connected with the upper coils of adjoining springs by links W. In this manner a smooth and even surface is pro- 70duced, preventing the mattress from sagging between the springs, which are mutually braced.

I claim and desire to secure by Letters Patent of the United States— 75

1. The combination, with the hinged head- 75 rest, of the T-shaped wire loops or supports hinged upon a transverse wire in said head- rest, as set forth.

2. The crimped-wire racks or ratchets L, 80 suitably secured to the longitudinal slats of the main frame, as set forth.

3. In a bed-bottom, the edge springs P, the top coils of which are provided at their outer edges with straight oblong loops Q, as set forth. 85

4. In a spring bed-bottom, the corner-springs R, the upper coils of which are provided with angular loops S, as and for the purpose set forth.

5. In a spring bed-bottom, the combination, 90 with the corner-springs having their upper coils provided with angular loops S, of the coils U, connecting the corners of the bed-frame with said angular loops, which are thereby supported, as set forth. 95

6. In a bed-bottom, the combination, with the frame, of the inner springs, O, the edge springs, P, the top coils of which are provided with straight oblong loops Q, the corner-springs R, the top coils of which are provided with angular loops S, and links T, connecting said loops Q and S, as set forth. 100

In testimony that I claim the foregoing as my own I have hereto affixed my signature in presence of two witnesses.

Witnesses: ISAAC CRUZAN.

A. V. HOUSE,
A. ENTSINGER.
